JAMES F. SHOOK, OF PHILLIPSBURG, NEW JERSEY, ASSIGNOR TO INGERSOLL-RAND COMPANY, OF JERSEY CITY, NEW JERSEY, A CORPORATION OF NEW JERSEY

ROCK DRILL

Application filed September 18, 1928. Serial No. 306,629.

This invention relates to rock drills, but more particularly to a fluid actuated rock drill of the type in which the piston or pistons reciprocate independently of the working implement.

A few of the objects of the invention are to expedite the drilling operation, to reduce vibration and shock incident to drilling to a minimum, to greatly increase the number 10 of blows of impact to the working implement within a given time, and in general, to protect the drilling mechanism against excessive strains and jars to which drills of this type are frequently subjected.

Other objects will be in part obvious and in part pointed out hereinafter.

In the drawings accompanying the specification and in which similar reference characters refer to similar parts,

Figure 1 is a sectional elevation of a rock drill constructed in accordance with the practice of the invention and showing the pistons in one of their limiting positions, and

Figure 2 is a view similar to Figure 1 showing the pistons in a reversed position.

Referring to the drawings, A designates generally a rock drill which for the purpose of illustration may be of a stoper type. The 30 rock drill A comprises an outer cylinder B carrying in this instance at its front end a front head C in which is disposed a chuck D for the reception and guidance of a working implement E, such as a drill steel. The 35 chuck D in this instance has a cavity F in its rearward end into which the working implement extends. In the form illustrated the front head C and the chuck D also serve as closures for the front end of the cylinder B. Preferably the cylinder B is provided with 40 a free exhaust port G for the escape of motive fluid to the atmosphere.

In accordance with the practice of the invention, the rock drill A is provided with an 45 inner cylinder H disposed concentrically within the cylinder B to form an annular piston chamber J between the cylinders. The inner cylinder H has a central chamber K and carries at its rearward end a flange L which overlies the rearward end of the cyl-

inder B and forms a closure for the corresponding end of the piston chamber J.

In order to centralize the cylinders B and H with respect to each other the flange L is provided with a projection O which extends 55 into and is in body engagement with the cylinder B. The inner cylinder H in this instance is also provided with a free exhaust port or passage P which leads from a point intermediate the ends of the piston chamber K and extends rearwardly through the cylinder H and the flange L where it opens to the atmosphere.

Disposed within the piston chamber K is a piston Q shown for the convenience of illustration as a plug piston of uniform diameter, and in the piston chamber J is a piston R of annular shape in slidable engagement with the interior surface of the cylinder B and with the exterior surface of the cylinder H. The pistons Q and R in this instance control 60 the free exhaust ports wherewith the respective piston chambers in which the pistons are disposed are provided.

Means is provided for transmitting the 65 blows of the pistons Q and R to the working implement E. To this end an anvil block S is disposed in the front end of the cylinder B and has a projection T at its forward end which extends slidably into the cavity F and is adapted to seat with its forward surface against the end of the working implement E. The anvil block S is preferably in slidable engagement with the inner surface of the cylinder B in order to form an additional 70 means for preventing leakage of pressure fluid from the front end of the piston chamber J. In the construction shown the anvil block S is provided at its rearward end with a stem U which projects through a bore V in 75 the front end of the cylinder H and into the path of the piston Q.

A closure is provided for the rearward end of the piston chamber K in the form of a back head W which in this instance has a 80 projection X extending into the piston chamber K for the purpose of centralizing the back head W with respect to the cylinders. Among other functions the back head W serves as a housing for a throttle valve Y 85

- which may be of the rotatable type and accordingly has a throttle lever Z for its manipulation. The throttle valve Y has a central chamber b which may be in constant communication with the pressure fluid supply and also has a port c which, in the open position of the throttle valve, registers with a passage d in the back head and leading to a supply reservoir e also in the back head.
- 10 The supply reservoir e may be an enlargement of and located intermediate the ends of a transverse bore f formed in the back head W. In the transverse bore f is disposed a bushing g having two annular rows of ports 15 h and j through which pressure fluid may flow from the supply reservoir e into a valve chamber k in the bushing g. The valve chamber k in this instance is formed by a pair of plugs o and p disposed in opposite ends of 20 the bushing g and spaced at their inner ends to form the valve chamber k. The plugs o and p may be held in operative position in any convenient manner, bolts q being indicated for this purpose.
- 25 The plugs o and p are provided with passages r and s respectively into which pressure fluid may flow from the valve chamber k. From the passage s to the rearward end of the piston chamber K leads a rearward inlet passage t for conveying pressure fluid into the piston chamber to impel the piston Q forwardly. A front inlet passage u leads from the passage r to the front end of the piston chamber K to convey pressure fluid 35 thereto for impelling the piston Q rearwardly.

In order to insure a simultaneous movement of the pistons Q and R in opposite directions so that one piston will be moving 40 forwardly while the other piston is moving in the opposite direction, a rearward inlet passage v is formed in the drill to lead from the passage r to the rearward end of the piston chamber J and a passage w is formed in 45 the drill to lead from the passage s to the front end of the piston chamber J. Due to this arrangement of the inlet passages pressure fluid may be simultaneously admitted to the rearward end of the piston chamber K 50 and into the front end of the piston chamber J to drive the pistons Q and R in opposite directions with respect to each other, and thus also pressure fluid may be simultaneously admitted into the rearward end of the piston chamber J and into the front end of 55 the piston chamber K.

Although the means for effecting the distribution of pressure fluid to the piston chambers forms no part of the present invention, 60 the drill however, is shown provided with a distributing valve x disposed in the valve chamber k to control the admission of pressure fluid into the passages r and s.

For the sake of simplicity of illustration 65 only two pistons are shown. It will, how-

ever, be readily apparent that the principle disclosed in the drawings is susceptible of further modification, depending upon the amount of drilling which it is desired to obtain within a given time and other considerations, such as weight and proportions of the 70 drill which the work for which it is intended will permit.

The advantages of the present invention will be readily apparent to those skilled in the art. Foremost of these advantages are the 75 elimination of vibration which will greatly prolong the life of the drill. Other advantages are the increased number of blows which may be delivered to the working implement 80 within a given period of time and the consequent greater footage of drilling that may be obtained by means of a drill thus constructed than is the case in the type of drills heretofore employed. These advantageous results 85 may be obtained without constructing the pistons of such proportions and weight as to be detrimental to the elements against which they strike or react.

The following description of the operation of the invention will be helpful in obtaining a clearer understanding of its advantages. The operation is as follows: With the throttle valve Y in the open position illustrated, pressure fluid enters the supply reservoir e thence flows through the ports j and h into the valve chamber k. With the valve x in the position illustrated pressure fluid flows into the passage r, thence through the inlet passage v into the rearward end of the piston chamber J to impel the piston R forwardly to deliver its blow against the anvil block S. At the same time pressure fluid will flow through the inlet passage u into the front end of the piston chamber K for impelling 100 the piston Q rearwardly.

As the pistons Q and R move in the directions described and after they have covered the exhaust ports of their respective piston chambers, the air in the ends of the piston chambers towards which the pistons are moving will be compressed and such compression will flow through the inlet passages w and t to act against the valve x for throwing it to its other limiting position.

When the piston R is about to deliver its blow and the piston Q reaches the rearward position in the piston chamber K, the exhaust ports G and P will be uncovered. This will permit the pressure fluid used for actuating the pistons to escape to the atmosphere and will therefore cause an abrupt drop in pressure in the passage r. The compression in the passage s then having reached its maximum degree together with such pressure fluid as may flow through the ports h to act against the valve will throw the valve x against the plug o to cut off the admission of pressure fluid into the passage r.

With the valve x reversed in the manner de-

scribed the passage of *s* will be uncovered. Pressure fluid will then flow from the valve chamber through the passages *s* and *t* into the rearward end of the piston chamber *K* to 5 drive the piston *Q* forwardly against the anvil block *S*. Likewise pressure fluid will flow from the passage *s* through the inlet passage *w* into the front end of the piston chamber *J* to act against the piston *R* for impelling 10 it rearwardly. After the pistons *Q* and *R* have moved to a point where they will cover the exhaust ports *P* and *G* respectively, the air in the front of the pistons will be compressed and will flow through the inlet passages *v* and *u* into the passage *r* to act against 15 the seated end of the valve *x* to again reverse it to its initial position, thus completing the cycle of operations.

I claim:

- 20 1. A rock drill, comprising an outer cylinder having a wall forming a piston chamber, an inner cylinder having a wall extending into the outer cylinder forming a piston chamber, a projection on one end of the inner 25 cylinder extending into the outer cylinder for centralizing the cylinders with respect to each other, said reciprocatory hammer piston chambers having exhaust ports, pistons in the piston chambers controlling the exhaust 30 ports, an anvil block slidably guided by the outer cylinder and associated with the piston chambers for transmitting the blows of the piston to an element intended to be actuated, valve means for effecting the distribution of 35 pressure fluid to the piston chambers, and ports and passages in the walls of the cylinders leading from the valve means to the piston chambers for conveying pressure fluid thereto to simultaneously actuate the pistons 40 in opposite directions with respect to each other.
2. A rock drill, comprising an inner cylinder having a wall forming a piston chamber, an outer cylinder spaced with respect to the 45 inner cylinder and having a wall forming an annular piston chamber, ports and passages in the walls of the inner and outer cylinders for the admission and exhaust of pressure fluid to and from the piston chambers, and 50 hammer pistons in the piston chambers actuated by the pressure fluid for delivering alternate blows to a working implement.
3. A rock drill, comprising an inner cylinder having a wall forming a piston chamber, 55 an outer cylinder spaced with respect to the inner cylinder and having a wall forming an annular piston chamber, inlet passages extending longitudinally along the walls of the inner and outer cylinders to admit pressure 60 fluid to one end of the piston chambers, exhaust ports in the walls of the inner and outer cylinders to exhaust pressure fluid from said piston chambers, hammer pistons in the piston chambers actuated by the pressure fluid for 65 delivering alternate blows to a working im-
